TORQUE WRENCH

Roy H. Van Horn, San Antonio, Tex.

Application July 11, 1939, Serial No. 283,783

12 Claims. (CL. 177—311)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in torque or tension wrenches and is primarily directed to the provision, in a wrench of this type, of means for notifying or warning the operator by visual or audible signal when the nut, bolt, or other object has been tightened to a desired torque or tension.

A common object of the improvements is to provide a tension wrench of novel and generally improved construction and design characterized by simplicity and ruggedness and having many advantages over other type tension wrenches particularly in respect to manufacturing costs, adaptability to use in close places, degree of accuracy, and dependability and directness of torque or tension indication.

The construction, arrangement, and combination of parts whereby the above and other objects and advantages of the invention are attained obviously may vary in different embodiments and the following detailed description and accompanying drawing is merely explanatory of one mode of applying the principle of the invention.

The invention is applicable to wrenches of either the open end or socket type but will be herein specifically described as applied to a wrench of the open jaw type illustrated in the accompanying drawing, wherein:

Figure 1 is a perspective view of the wrench;
Figure 2 is a view thereof partly in elevation and partly in section;

Figure 3 is a cross section on line 3—3 of Figure 2, and

Figure 4 is a detail view, on an enlarged scale, of various units of the signal circuit.

Briefly the invention comprises a wrench, in which there is a relative bending or pivotal movement between the jaw or socket and the handle whenever the device to which the wrench is applied resists the turning force applied to the handle, and which is so constructed that the amount of spring or bend in the handle of the wrench can be measured accurately in terms of foot pounds or other units of force applied to the bolt, nut, or other device to be tightened. The wrench is provided with electric signaling means including a lamp, bell, buzzer or other suitable device in series with circuit maker and breaker points operated by the movement of the handle to close

the circuit when the deflection of the handle corresponds to a desired tension.

In the drawing, 1 represents the head of the wrench and 2 the shank or handle portion upon which is secured the grip or handle proper 3. The wrench head is provided with jaws 4 for engaging a nut or other element to be turned and at a minimum distance approximately one and one quarter inches from center of opening in the jaw end of the wrench a short flat spring 5 connects the head 1 and the shank 2. This spring provides a flexible or elastic connection between the wrench head and the wrench handle whereby the latter is adapted to bend or be deflected from its normal position under a given load or force applied to the handle 3 when turning or tightening a nut, etc. When the head 1 and shank 2 are formed as integral parts of a single piece of thick rigid stock, as illustrated in the drawing, a portion of the stock adjacent the head is flattened or reduced in cross section to form the spring 5. The shank 2 has a flat 6 on one side but otherwise is circular in cross section and provided with external screw threads as shown. It is provided with an axial chamber or cavity 7 extending inwardly from the free end of the shank and terminating short of the opposite end of the shank a distance sufficient to leave a substantial thickness of material between the cavity and the spring 5. The chambered portion of the shank serves as a housing for a signal lamp and associated parts and is apertured at diametrical points near its open end to provide sight openings or windows 8. An elongated opening 9 for a conductor is located in the side of the shank near the closed end of the cavity.

The lamp may be of any conventional or desired construction adapted to be enclosed in the windowed end of the cavity 7 so as to be visible through the windows 8. A suitable construction comprises a small glass bulb 10 secured at its lower portion within an encircling ring or band 11 of metal to which is electrically connected one end of the lamp filament. The bulb and conductor are mounted in a metallic holder comprising a socket 12 in which the bulb and conductor are fixed and a base disk or flange 13 to which the other end of the lamp filament is electrically connected; the holder and conductor ring insulated one from the other. The outside diameter of the socket is such that it has a snug sliding fit in the end of a tube 14 of insulation material with which the cavity 7 is lined. An attenuated dome or cover 15 of thin metal has a snug fit on the inside of the insulating tube 14 and is

anchored in place by a short, covered, conductor wire 16 extending through the elongated opening 9 of the shank and secured at one end to the dome 15 and at the other end to the member 17 as shown in Figure 2. When the lamp is inserted in the open end of the shank, the conductor band 11 is telescoped by the open end of the dome which thus serves as an electrical conductor between the band and the covered wire. The tube 14 and the dome 15 are suitably apertured in line with the windows 8 so as not to obstruct the view to the lamp.

For the size wrench shown, a small 2 volt electric lamp is used and the required voltage is supplied by two small flash light batteries 18 of 1 volt each. These are contained in the handle 3 which is a hollow barrel or cylinder internally screw threaded at one end to receive the threaded shank 2 and externally threaded at its opposite end to receive a screw cap 19.

The two batteries are arranged in tandem with the foremost battery held in electrical contact with the base 13 of the lamp by the pressure of a spring 20 between the outermost battery and the cap. The handle 3 has a tubular lining 21 of insulating material and also windows 22 in line with windows 8 of the shank.

Integral with the head 1 and extending outwardly thereof and over relatively opposite sides of the spring 5 are two curved horn-like projections 23 constituting one set of switch points or contacts. Another set of switch points or contacts comprises two rods 24 mounted in the member 17 which has a collar encircling the shank 2 between the handle 3 and the spring 5. The collar is insulated from the shank by a two-part flanged sleeve bushing 25 of insulating material but is electrically connected, by solder or otherwise, to the conductor wire 16. Collar 17 and insulating bushing 25 have a slide fit on the threaded shank 2 and are held against longitudinal displacement from a given position by means of front and rear lock nuts 26. Each bushing is provided with inner and outer plane faces or flats; the inner flats 27 being adapted to cooperate with the flat side 6 of the shank 2 to prevent turning of the bushings on the shank, and the outer flats 28 being adapted to cooperate with a flat (not shown) in the bore of the collar 17 to prevent any rotation between the bushing and the collar. These flats are so correlated with the opposed sets of contact points 23 and 24 as to insure proper alignment of the points when assembling and using the wrench.

Contact points 23 are electrically connected to one terminal of the lamp filament by the shank 2, barrel 3, cap 19, spring 20, batteries 18, and lamp base 13. Contact points 24 are electrically connected to the other terminal of the lamp filament by the collar 17, wire 16, dome 15, and conductor ring 11. Points 23 and 24 normally are spaced apart to provide a gap or break in the signal circuit and the length of gap determines the amount of bent or deflection of the handle required to move the points on one or the other side of the wrench together closing the gap and completing the circuit. In order that the size of the gap may be varied, the contact rods 24 are made adjustable. To this end, the rods have a slide bearing on the smooth bores of cylindrical bearing lugs 29 forming integral parts of the collar 17 on relatively opposite sides thereof as shown. Nuts 30 are screwed on opposite ends of the rods for adjusting and locking the rods in position. Each rod carries a pointer 31

working in a longitudinal slot 32 in its respective bearing lug and reading against scale marks 33 calibrated to indicate the torque or tension, placed on the nut or bolt in the tightening operation, corresponding to various degrees of deflection of the wrench handle. The scale may be calibrated in inch pounds, foot pounds, or other desired and appropriate units of measurement.

In use, the points 24 are adjusted until the pointers are opposite the scale marks corresponding to the maximum torque or tension according to which the nut or other element is to be tightened. The wrench is applied to the nut and turned in the usual manner by pressure exerted on the handle. As the nut tightens, the resistance thereof to the turning of the wrench increases proportionately and when this resistance exceeds the strength of the spring, the handle of the wrench bends at this place. The deflection of the handle from its normal position flexes or tensions the spring to exert an increased torque on the nut proportionate to the bending or deflection of the handle. When the deflection is such that one or the other paired contact points 23 and 24 engage the signal circuit is closed and the signal lamp is lighted, indicating that a desired tension has been reached. The operator can tell by the flash of light when the desired tension has been attained even though the position of the wrench is such that a direct view of the indicator is impossible.

The accuracy required to obtain the proper tension on small bolts used in aircraft construction can only be obtained by a sensitive tension wrench. By utilizing the electric light and contact points with the principle developed in the subject wrench, this accuracy can be obtained within the limit of one pound or less. The difficulty encountered in aircraft construction particularly, i. e. working in close places, necessitates the use of small compact wrenches. The design and construction of this wrench is such that it will meet these requirements.

Having thus described the invention, I claim:

1. In a leverage indicating device, in combination, a lever flattened for a portion of its length and inwardly of its ends to provide a thin flexible section between thick rigid outer sections, said flexible section being adapted to bend under a given load sufficient to cause deflection of one rigid section from its normal position with respect to the other section, and a normally open electric circuit including positive and negative terminals on the said rigid sections respectively of the lever and normally spaced apart but adapted to contact each other across the flexible section at a pre-selected relative deflection of the rigid sections whereby to close the said circuit.

2. In a leverage indicating device, a lever having a flexible elastic portion adapted to bend under a predetermined stress and through an angle which is proportional to the torque or leverage, and a normally opened signal circuit including circuit closing elements mounted on the lever adjacent each end of the bendable portion, the elements at one end of the bendable portion being complementary to and spaced from corresponding elements at the other end of the said bendable portion and adapted to be moved into contact therewith by the bending of the lever through a pre-selected angle to close the circuit, said circuit closing elements being manually settable to close the circuit at any desired angle within the bending range of the lever.

3. An electric indicating torque wrench comprising a head and a shank forming integral parts of a single piece of comparatively thick rigid stock reduced in cross section at the junction of the head and shank to provide a thin flat elastic portion bendable under a given stress to permit deflection of the shank from a normal position with respect to the head, and an electric signal circuit including a signal member carried by the shank and co-operating circuit controlling contacts mounted on the head and shank respectively and adjacent the bendable portion to be moved into and out of mutual engagement by a predetermined deflection and return of the shank with respect to its normal position.

4. An electric indicating torque wrench comprising a head and a shank forming integral parts of a single piece of comparatively thick rigid stock reduced in cross section adjacent the head to provide a thin flat elastic portion bendable under a given stress to permit deflection of the shank from a normal position, and an electric signal circuit including a signal member mounted on the shank near its free end and co-operating circuit controlling contacts mounted on the wrench at opposite sides of the bendable portion to be moved into and out of mutual engagement by a predetermined deflection and return of the shank with respect to its normal position, said contacts being adjustable to cause the circuit to be closed at any desired tension within the range of the wrench corresponding to a given deflection of the shank.

5. A torque wrench comprising a head adapted to be engaged with an element to be turned, a shank having a flexible connection with the head whereby it is adapted to be deflected from a normal position with respect to the head under a given force applied to the handle when turning the said element, a chambered handle secured to the shank and having windows therein, a lamp in said handle and visible through the windows, a battery in said handle, a set of contact points on the said head and extending rearwardly over the flexible connection, and another set of contact points on the said shank and extending forwardly over the flexible connection in line with the first set to be engaged therewith by a deflection of the shank to close an electrical circuit through the lamp, one set of points being electrically and directly connected to one terminal of the battery and the other set being electrically connected through the lamp to the other terminal of the battery.

6. A torque wrench comprising a lever consisting of thick head and shank portions integrally connected by a substantially flat thin spring portion adapted to be flexed by a deflection of the shank, a pair of contact points fixed to said head on opposite sides thereof and projecting over the said spring portion, a pair of contact points on the said shank and adjustable to be lined up with fixed contact points for engaging the latter at a preselected deflection of the said shank, a signal lamp connected in an electric circuit with the said fixed and adjustable contact points to be lighted when the circuit is closed by the engagement of the contact points, an adjustment scale on the said shank calibrated to indicate the torque corresponding to various degrees of deflection of the shank, and index means on the adjustable contact points.

7. An electric indicating torque wrench comprising a lever consisting of rigid head and shank portions integrally connected by a flat thin spring

portion whereby the shank portion is adapted to be deflected with respect to the head portion under a predetermined applied torque, handle and a set of contact points operatively connected to the said head portion and extending laterally therefrom and over relatively opposite side faces of the spring portion, a set of contact points carried by and insulated from the shank portion for engagement with the contact points of the head portion, means for maintaining the points of one set in alignment with corresponding points of the other set, said sets being spaced apart to provide in the absence of applied torque an air gap between corresponding contact points and adapted to be electrically connected when the deflection of the shank is such as to close the gap between corresponding points, and a signal lamp in the chamber of the shank and electrically connected to the sets of contact points.

20 8. A torque indicating wrench comprising an inflexible work-engaging member, an inflexible handle member, a short, straight flat spring rigidly connected at one end to the work-engaging member and rigidly connected at the other end to the handle member to provide a flexible elastic connection between the said inflexible members adapted to be flexed by force applied thereto through the handle member, electrical signal means, electrical contact elements arranged in circuit with the signal means and operatively associated with the said members whereby a contact element associated with one of the members will engage a corresponding contact associated with the other member to close the circuit to the signal means when the said spring is flexed to a predetermined amount.

9. A torque indicating wrench comprising an inflexible work-engaging member, an inflexible handle member, a substantially short straight flat spring connected at one end rigidly to the work-engaging member and at the other end rigidly to the handle member to provide a flexible elastic connection between and serving to longitudinally space apart the said members whereby the latter are adapted to be deflected relative to one another about an axis located between the rigidly connected ends of the spring electrical signal means, contact elements associated with the handle and extending forwardly beyond the spring-connected end thereof and on relatively opposite sides of the spring, means in circuit with the signal means and associated with the work-engaging member to extend rearwardly of its spring-connected end to engage the contact elements of the handle member to close the circuit to the signal means when the latter member is deflected a predetermined amount.

10. A torque indicating wrench comprising an inflexible work-engaging member, an inflexible handle member, a short double concave spring rigidly connected at one end to the work-engaging member and rigidly connected at its other end to the handle member to provide a flexible elastic connection between the members adapted to be flexed by force applied thereto through the handle member, and a warning device, actuating means therefor including control elements movable into various positions relative to each other including a critical position at which the actuating means is energized, said elements being mounted on the work-engaging member and the handle member respectively to be moved into the critical position by and upon a predetermined deflection of the spring.

11. A torque indicating wrench comprising a

work-engaging member, a handle member, a short double concave spring connected at one end rigidly to the work-engaging member and at the other end rigidly to the handle member to provide a flexible elastic connection between and serving to longitudinally space apart the said members whereby said members are adapted to be deflected relative to each other about an axis substantially at the center of the spring, electric signal means, an electrical contact element associated with the work-engaging element and in circuit with the signal means, and means associated with the handle member arranged to engage the said electrical contact element to complete a circuit for operating the signal means when the said members have been relatively deflected a predetermined amount.

12. A torque indicating wrench comprising a work-engaging member consisting of a forwardly disposed jaw portion and a rearwardly disposed

shank portion integrally connected therewith and a pair of curved horn-like projections integrally connected with the jaw portion adjacent the junction of the latter with the shank portion 5 and extending outwardly therefrom and rearwardly over the shank on relatively opposite sides of the member, said shank portion being reduced in cross section over a small area adjacent the jaw portion to provide a short flexible elastic section adapted to be flexed under a given load applied to the shank portion, electrical signal means arranged in circuit with the said projections, means associated with the shank portion and arranged beyond the flexible section thereof 10 to engage the said projections when the said section has been flexed a predetermined amount to thereby close the circuit for operating the signal means, and a handle on the said shank portion.

ROY H. VAN HORN.
